FIG. 2

Des. 201,323

PAGE 2

FIG. 3

FIG. 4

FIG. 5

FIG. 1 is a front perspective view of a sewing machine showing my new design;

FIG. 2 is another front perspective view thereof as it appears turned at a slightly different angle;

FIG. 3 is a rear plan view thereof;

FIG. 4 is a rear perspective view of the sewing machine shown in FIGS. 1 and 2; and

FIG. 5 is an end view taken from the right-hand side of the sewing machine shown in FIGS. 1 and 2.

I claim:

The ornamental design for a flat bed sewing machine, substantially as shown.
